CLAIM

The ornamental design for a display screen with an animated graphical user interface, as shown and described.

DESCRIPTION

FIG. 1 is a front view of a display screen with an animated graphical user interface showing a first image in the first embodiment of our new design.

FIG. 2 is a second image thereof.

FIG. 3 is a third image thereof.

FIG. 4 is a fourth image thereof; and,

FIG. 5 is a fifth image of the second embodiment wherein FIGS. 1-4 show the first, second, third, and fourth images thereof.

The broken lines showing a mobile device illustrate environmental structure and form no part of the claimed design. All other broken lines in the drawings, including the gray dashed lines, depict portions of the graphical user interface that form no part of the claimed design.

The appearance of the graphical user interface sequentially transitions between the images shown in FIGS. 1-4. In another embodiment, the appearance of the graphical user interface sequentially transitions between the images shown in FIGS. 1-5. The process or period in which one image transitions to another image forms no part of the claimed design.
